UNITED STATES PATENT OFFICE.

JOHN A. MOFFAT, OF HAMILTON, ONTARIO, CANADA.

IMPLEMENT FOR APPLYING GLAZIERS' POINTS.

1,240,473.

Specification of Letters Patent. Patented Sept. 18, 1917.

Application filed April 14, 1917. Serial No. 162,105.

To all whom it may concern:

Be it known that I, JOHN A. MOFFAT, a subject of the King of Great Britain, residing at Hamilton, in the Province of Ontario and Dominion of Canada, have invented certain new and useful Improvements in Implements for Applying Glaziers' Points, of which the following is a specification.

10 This invention relates to improvements in implements for inserting glaziers' points in sash members to hold the glass in position prior to the application of the putty or other cement, and has for one of its objects 15 to improve the construction and increase the efficiency and utility of implements of this character.

Another object of the invention is to provide an implement of this character including a detachable abutment or driving member, whereby the driving member may be renewed when worn, without discarding the remainder of the implement.

Another object of the invention is to provide an implement of this character having a driving or abutment member detachably and reversibly arranged in the stock of the implement, so that the abutment member may be reversed in position when one driving edge becomes worn or impaired.

With these and other objects in view, the invention consists in certain novel features of construction, as hereinafter shown and described and then specifically pointed out 35 in the claims; and in the drawings illustrative of the preferred embodiment of the invention—

Figure 1 is a view of a portion of a window sash and a portion of the glass supported upon the rabbet of the same with the implement shown in operative position.

Fig. 2 is a section on the line 2—2 of Fig. 1.

Fig. 3 is an enlarged perspective view of 45 a portion of the improved implement illustrating its construction.

Corresponding and like parts are referred to in the following description and indicated in all the views of the drawings 50 by the same reference characters.

The glass is usually supported in position within the rabbet of the sash by triangular shaped members called glaziers' points and constructed of sheet metal, usually zinc, and 55 are forced into the sash and in contact with the glass prior to the application of the

putty. Heretofore these points have been driven into the sash by blows imparted thereto by the side edge of a chisel or like implement, but this operation is tedious and 60 the glass is liable to be scratched or broken by careless handling of the implement. The implement which is disclosed in this application is designed to force the "points" into the sash without danger of breaking or 65 marring the glass and at the same time causing the points to bear with requisite pressure against the glass to hold the latter in place. For the purpose of illustration a portion of a sash is represented as a whole 70 at 10, and provided with the usual rabbet 11 for supporting the glass, a portion of the latter being represented at 12. One of the points is indicated at 13 after it has been forced into the body of the sash, and 75 another of the points is represented in position to be forced into the sash.

The improved implement comprises a stock or body of coacting portions 14—15, the portion 14 being directed obliquely to 80 the longitudinal axis of the stock. The portion 15 has an operating handle 16 attached thereto, as shown. The portion 14 of the stock is formed with a flat face 17 and with a transverse recess indicated at 18 spaced 85 from its free end. The portion of the stock in advance of the recess 18 is reduced in thickness and the reduced portion curved away from the recess, as shown at 19. The end of the reduced portion of the stock is 90 rounded or concaved, as represented at 20.

Fitting within the recess 18 is a block device 21, preferably of hardened steel, the outer face of the block being flush with the face 17 of the stock. The block is detachably supported within the recess 18 by a clamp screw 22 or other suitable fastening device. When thus arranged the edge of the block 21 is located next to the curved face 19 of the reduced portion of the stock, 95 the curved face 19 and the block 21 coacting to produce a recess with the outer face of the block forming the inner wall of the recess.

With an implement thus constructed when 105 the flat face 17 and the outer face of the block 21 are disposed upon the glass 12, the handle 16 will stand obliquely to the longitudinal plane of the glass and thus provide space for the fingers of the operator, so that 110 the flat faces may bear upon the glass in operating the implement. After the glass 12

has been located in position upon the rabbets 11 of the sash, a number of the members 13 are thrown indiscriminately upon the glass and the implement employed to separate 5 one of the points from the others and push it over the glass with one of the terminals in position where the point is to be inserted. The implement is then disposed in position over the point with the forward edge of 10 the block 21 against the adjacent edge of the point, as illustrated in Fig. 1. Pressure is then applied to the handle 16 to force the point into the sash until the rounded end 20 bears against the sash. If the material of 15 the sash is abnormally hard the implement is moved from side to side with a rolling motion to vibrate the member 13 laterally to assist in forcing it into the sash. The rounded end 20 materially aids in the operation by 20 enabling the implement to be given the requisite rolling or vibratory motion. The face 17 and the outer face of the member 21 lying flatly upon the glass cause the shoulder or abutment portion of the mem- 25 ber 21 to effectually coact with the point 13 in forcing the latter into the sash, while at the same time the rounded terminal being disposed in advance of the forward edge of the member 21 limits the inward movement 30 of the point and leaves the latter projecting to the requisite extent, generally about an eighth of an inch.

The block 18 is preferably square, or corresponding in width to the width of the 35 portion 14 of the stock, while the recess 18 is of corresponding size. Then by forming the block 21 with all four edges flat, when one edge is worn the block can be reversed in position to bring another of the edges in 40 operative position. Thus the "life" of the implement is materially increased without increasing the expense or weight. When the member 21 is worn out or impaired it can be renewed at a trifling expense without the 45 necessity of discarding the remainder of the implement.

The improved device is simple in construction, can be inexpensively manufactured and sold at a small expense, and will be found 50 very convenient for glaziers in applying "points" to the sash.

Copies of this patent may be obtained for five cents each, by addressing the "Commissioner of Patents, Washington, D. C."

The stock portion 14-15 may be of relatively soft metal, such as brass, cast-iron, malleableized or not as may be preferred, while the member 21 will preferably be of 55 hardened steel to enable it to withstand the friction or impact of the members 13.

Having thus described the invention, what is claimed as new is:

1. An implement of the class described 60 comprising a stock having a handle at one end and a transverse seat spaced from the other end, the body of the stock being reduced in advance of the seat with the lower face of the reduced portion curving up- 65 wardly and outwardly away from the seat, and a block secured within the seat with its outer face flush with the adjacent face of the stock and its forward edge forming a glazier's point engaging abutment, the 70 curving of the lower face of the reduced portion operating to prevent the separation of the abutment from the glazier's point in event of the stock being elevated at its handle end. 75

2. An implement of the class described 80 comprising a stock having a handle at one end and a transverse abutment spaced from the other end, the body of the stock in advance of the abutment being reduced with 85 the lower face of the reduced portion curving upwardly and outwardly away from the abutment, the curving of the lower face of the reduced portion operating to prevent the separation of the abutment from the glazier's 90 point in event of the stock being elevated at its handle end. 95

3. An implement of the class described 100 comprising a stock having a handle at one end and a transverse abutment spaced from the other end, the body of the stock in advance of the abutment being reduced with the forward face of the reduced portion rounded and the lower face curving up- 105 wardly and outwardly away from the abut- 110 ment, the curving of the lower face of the reduced portion operating to prevent the separation of the abutment from the glazier's point in event of the stock being elevated at its handle end.

In testimony whereof I affix my signature.
JOHN A. MOFFAT. [L. s.]
